MEANS FOR SUPPORTING OSCILLATING
MASSES

Tibor von Melczer, Budapest, Hungary

Application June 23, 1931, Serial No. 546,414,
and in Hungary June 25, 1930. Renewed July
20, 1933

5 Claims. (Cl. 308—2)

This invention relates to an arrangement for supporting oscillating masses in a practically frictionless manner. The new arrangement is more particularly suitable for measuring instruments and the like, where, for the purpose of ensuring the greatest possible accuracy, the resistances due to friction have to be reduced to a minimum.

In the arrangement according to the invention 10 the oscillating masses are supported along an edge which bears against its supporting body along a straight line. There are known arrangements in which, with the same object in view, the oscillating masses are supported in a point 15 and others, in which they are supported along a straight line. These arrangements, however, have the disadvantage that the means of support gives a sure support in general only with respect to forces acting in a single definite direction, but does not suffice for the support of 20 or for withstanding forces acting in other directions.

This disadvantage is overcome in the arrangement according to the invention, which is suitable 25 for the support of oscillating masses, that is to say, masses in which the forces may act in any direction on the means of support.

The new arrangement consists substantially 30 of at least two coaxial, helical bodies which make contact with one another along their common geometrical axis in a line, one helical body supporting the oscillating masses and the other helical body being preferably stationary. The depth 35 of thread is equal to the radius of the helical body.

The invention shall now be more particularly 40 described with reference to the accompanying drawing.

Fig. 1 is a plan view and Fig. 2 a cross-section 45 of a known arrangement.

Fig. 3 a plan view and Figs. 4 and 5 two different cross-sections of a constructional form of the arrangement according to the invention,

Fig. 6 a plan view, Fig. 7 a longitudinal section 50 and Fig. 8 a cross-section of another constructional form of the invention.

In Figs. 1 and 2 A is a bar having a semi-circular cross-section and B a bar having an acute segment-shaped cross-section. The bar B 55 rests along its edge C on the bar A. If the bar A be held rigidly and the oscillating masses be connected to the bar B, the oscillation takes place in a known manner, practically without friction about the edge C, when the forces act as nearly as possible perpendicularly with respect to the

supporting surface D, so that no appreciable lateral thrust is produced.

If, however, the two bars A and B be twisted with the same amount of twist about the edge C as the common axis, the arrangement according to Fig. 3 results, the cross-sections I—I and II—II of which are shown in Figs. 4 and 5. The straight line C, that is, the line of contact of the two bars, is now the geometrical axis of the two helical bodies A and B and still forms the axis of the oscillations. Owing, however, to the helical form of the two bodies A and B, it is possible to load the body B with forces acting in any direction, while the line of contact cannot become displaced.

The amplitude of the rocking motions is determined by the width of the gap E or the size of the angle α .

Figs. 6, 7 and 8 show another constructional form with ribbon-shaped helical bodies A and B, 75 which have the same pitch and are of different thickness a and b and are inserted one in the other. In the example shown the helical body A has a somewhat greater diameter than the helical body B and is supported at F and G. 80 The oscillating mass is connected in any suitable manner with the helical body B. The amplitude of the rocking motion is determined by the angle α , which with a given pitch can be 85 made of any size within wide limits by suitably selecting the thicknesses a and b of the helical bodies.

The depth of thread of each helical body is equal to its radius. In this constructional form 90 the two helical bodies do not make contact with one another along an edge, but along a straight line, which, however, also lies in the common geometrical axis of the two helical bodies. The helix B, for instance, may on the other hand 95 be made of triangular cross-section, such that it rests along the edge on the helical body B.

The invention may also be carried into effect with more than two helical bodies introduced one into the other.

What I claim is:

1. In an arrangement for supporting oscillating masses in a frictionless manner, two coaxial helical bodies which have their convolutions inserted one in the other and make contact with one another along their common geometrical axis in a straight line, one of the two said helical bodies being connected to the oscillating mass and the other helical body forming the support for the first-named helical body, as and for the purpose set forth.

2. In an arrangement for supporting oscillating masses in a frictionless manner, two coaxial helical bodies of the same pitch, which have their convolutions inserted one in the other and make contact with one another only along their common geometrical axis, the depth of thread of each helical body being equal to its radius, the helical bodies having different diameters and being separated from one another by continuous gaps, one helical body being adapted to support the oscillating mass and the other helical body to form the support for the first-named helical body, as and for the purpose set forth. 80
- 5 3. In an arrangement for supporting oscillating masses in a frictionless manner, two coaxial helical bodies of the same pitch, which have their convolutions inserted one in the other and make contact with one another only along their common geometrical axis, the depth of thread of each helical body being equal to its radius, and the two helical bodies being separated from one another by continuous gaps, one helical body being adapted to support the oscillating mass and the other helical body to form the support for the first-named helical body, as and for the purpose set forth. 85
- 10 4. In an arrangement for supporting oscillating masses in a frictionless manner, two coaxial helical bodies of the same pitch, which have

their convolutions inserted one in the other and make contact with one another only along their common geometrical axis, the depth of thread of each helical body being equal to its radius, but the thickness of one helical body differing from the thickness of the other, and the two helical bodies being separated from one another by continuous gaps, one helical body being adapted to support the oscillating mass and the other helical body to form the support for the first-named helical body, as and for the purpose set forth. 90

15 5. In an arrangement for supporting oscillating masses in a frictionless manner, two coaxial helical bodies of the same pitch, which have their convolutions inserted one in the other and make contact with one another only along their common geometrical axis, the depth of thread of each helical body being equal to its radius, and the two helical bodies being separated from one another by continuous gaps, one helical body being adapted to support the oscillating mass and the other helical body to form the support for the first-named helical body, as and for the purpose set forth. 95
